UNITED STATES PATENT OFFICE.

CHRIS SORENSEN, OF TACOMA, WASHINGTON.

PISTON.

Application filed January 7, 1927. Serial No. 159,719.

This invention relates generally to engine pistons, but more particularly to the type of pistons used in internal combustion engines and having a skirt or tubular portion extending inwardly from the piston head.

The primary object of my invention is to provide an inexpensive self-adjusting piston of this kind having a resilient skirt portion so split as to not unduly weaken the piston, but to permit sufficient expansion and contraction as takes place from temperature changes under ordinary conditions of use so as to insure ordinary fitting of the piston in its cylinder at all times.

15 A further object is to provide a piston of the above kind which will be of such rigidity and construction as to have all of the advantages of a completely rigid piston, but to at the same time, have the added 20 advantage of automatically keeping a snug fit in the cylinder in the presence of temperature changes.

Another object is to provide a self-adjusting split-skirt piston, a maximum portion 25 of the skirt of which is preserved in rigid form for providing a most efficient bearing surface and at the same time insuring maximum strength and reliable support for the wrist pin bearing bosses.

30 Still another object is to provide a most practical means for insuring uniform expansion and contraction of the flexible part of the skirt portion of the piston from end to end.

35 Other objects will become apparent as the nature of the invention is better understood, and the same consists in the novel form, combination and arrangement of parts hereinafter more fully described, shown in the 40 accompanying drawing and claimed.

In the drawing, wherein like reference characters indicate corresponding parts throughout the several views,

Figure 1 is an elevational view of a piston 45 constructed in accordance with my invention;

Figure 2 is a central longitudinal section on line 2—2 of Figure 1;

Figure 3 is a central longitudinal section 50 on line 3—3 of Figure 2; and

Figure 4 is a transverse section on line 4—4 of Figure 2.

Referring more in detail to the drawing, the present piston includes a hollow rigid 55 head 5 having the usual annular packing ring receiving grooves 6. Extending in-

wardly from and integral with the piston head 5 is the tubular skirt or body 7 which has the usual transverse opposed and inwardly projecting wrist pin bearing bosses 8. 60 The head 5 is reinforced by an internal rib 9 which includes a straight intermediate portion extending diametrically across the inner face of the outer end wall of the head and opposed end portions which extend inwardly 65 on the inner surface of the cylindrical wall of the head and join with the outer sides of the bosses 8 as at 10 so as to reinforce and lend effective support for the latter.

As shown more clearly in Figure 2, the 70 major portion of the skirt is of a diameter slightly greater than that of the head and the latter includes an annular reduced land 11 of uniform width at the inner side of the innermost groove 6. The portions of the skirt surrounding the bosses 8 are externally reduced from the land 11 inwardly to a point slightly beyond said bosses as at 12 75 to provide relief areas 13 that are eccentric to the skirt and merge with the outer surface of the latter as at 14 adjacent to and at opposite sides of the bosses. This leaves tapering shoulders 15 at the inner sides of the adjacent portions of land 11 narrower 80 than the shoulders formed at 12.

A circumferentially extending slot 16 85 partly severs the head from the skirt at the inner side of the land 11, and this slot extends for approximately 60 degrees of the circumference of the piston, starting at a point 16^a midway between the bosses 8 and extending to the nearest adjacent point 14 where one of the relief areas 13 merge with the normal portion of the skirt. Further, 90 the skirt is divided longitudinally by means of an inclined or oblique slot 17 whose slant is approximately 7 degrees and which extends from the end of the slot 16 which is nearest a boss 8 to the inner end of the skirt and in a direction away from this boss. This renders the skirt approximately 60 degrees 95 resilient and 300 degrees rigid or solid, and defines a resilient flexible skirt part 18 bounded on two sides by the slots.

100 Approximately midway between the ends of the skirt 7 the latter is provided with a circumferentially extending internal rib 19 which extends on the part 18 from a point about midway between the ends of slot 16 105 away from slot 17 to the boss 8 farthest from the slot 17. This rib 19 prevents the 110 flexible part 18 of the skirt from caving in

and distributes the tension on that part of the skirt uniformly from end to end. This rib 19 is aided in these functions by an inwardly directed flange or fillet 20 provided entirely around the inner end of the skirt.

From the above, it will be seen that I have provided a piston which is about 300 degrees rigid and which provides this amount of the body for support of the wrist pin bearing bosses. In view of this fact, the piston will not readily cave in or become distorted in service by close fitting, as is experienced with prior constructions in which the skirt portion is severed to a much greater degree or extent from the head. Moreover, objectionable stiffening struts between the sides of the bearing bosses and the skirt are rendered unnecessary, and the possibility of cylinder 20 scoring is minimized.

Minor changes may be made without departing from the spirit and scope of the invention as claimed.

It is noted that the present piston is quite efficient without the provision of the relief areas 13 and they may accordingly be eliminated without departing from the spirit of the invention.

What I claim as new is:—

30 1. A piston having a head, a skirt, and wrist pin bearing bosses, the head on both sides of one of the bearing bosses and one side of the other bearing boss being integral with the skirt, the skirt being separated from 35 the head at the other side of said other bearing boss by a circumferentially extending slot and being divided by a longitudinal slot communicating with said circumferentially extending slot, thereby rendering the slotted 40 side of the skirt partly resilient, and means to distribute the tension on the resilient skirt part uniformly from end to end of the latter, said last named means embodying a circumferentially extending rib formed internally 45 of the skirt and extending partly across said resilient part of the skirt.

50 2. A piston having a head, a skirt, and wrist pin bearing bosses, the head on both sides of one of the bearing bosses and one side of the other bearing boss being integral with the skirt, the skirt being separated from the head at the other side of said other bearing boss by a circumferentially extending slot and being divided by a longitudinal slot 55 communicating with said circumferentially extending slot, thereby rendering the slotted side of the skirt partly resilient, and means to distribute the tension on the resilient skirt part uniformly from end to end of the latter, said last named means embodying a circumferentially extending rib formed internally of the skirt and extending partly 60 across said resilient part of the skirt, said

rib being located between the ends of the skirt, and a divided fillet extending entirely 65 around the inner end of the skirt.

3. A piston having a head, a skirt, and wrist pin bearing bosses, the head on both sides of one of the bearing bosses and one side of the other bearing boss being integral 70 with the skirt, the skirt being separated from the head at the other side of said other bearing boss by a circumferentially extending slot and being divided by a longitudinal slot communicating with said circumferentially extending slot, thereby rendering the slotted side of the skirt partly resilient, there being a relieved peripheral area about the end of each bearing boss, and said circumferentially extending slot extending from a point midway between the bearing bosses to the adjacent side of one of said relieved areas. 75

4. A piston having a head, a skirt, and wrist pin bearing bosses, the head on both sides of one of the bearing bosses and one side of the other bearing boss being integral 80 with the skirt, the skirt being separated from the head at the other side of said other bearing boss by a circumferentially extending slot and being divided by a longitudinal slot 85 communicating with said circumferentially extending slot, thereby rendering the slotted side of the skirt partly resilient, there being a relieved peripheral area about the end of each bearing boss, and said circumferentially extending slot extending from a point midway between the bearing bosses to the adjacent side of one of said relieved areas, said longitudinal slot extending obliquely of the skirt from the end of the circumferential 90 slot terminating at said relieved area toward but short of the longitudinal plane of the piston at which the other end of said circumferential slot terminates. 95

5. A piston having a head, a skirt, and wrist pin bearing bosses, the head on both sides of one of the bearing bosses and one side of the other bearing boss being integral with the skirt, the skirt being separated from the head at the other side of said other bearing boss by a circumferentially extending slot and being divided by a longitudinal slot 100 communicating with said circumferentially extending slot, thereby rendering the slotted side of the skirt partly resilient, said circumferential slot extending for approximately 105 sixty degrees of the circumference of the skirt, and said longitudinal slot extending obliquely at an angle of approximately seven degrees from the end of the circumferential slot which is nearest said other bearing boss toward the longitudinal plane of the piston 110 at which the other end of the circumferential slot terminates. 115

In testimony whereof I affix my signature:
CHRIS SORENSEN.
